UNITED STATES PATENT OFFICE.

HENRY H. WARNER, OF TACOMA, WASHINGTON.

LETTER-BOX.

SPECIFICATION forming part of Letters Patent No. 757,698, dated April 19, 1904.

Application filed July 19, 1902. Serial No. 116,250. (No model.)

To all whom it may concern:

Be it known that I, HENRY H. WARNER, a citizen of the United States, residing at Tacoma, in the county of Pierce and State of Washington, have invented certain new and useful Improvements in Letter-Boxes; and I do hereby declare the following to be a full, clear, and exact description of the invention, such as will enable others skilled in the art to which it appertains to make and use the same.

The object of my invention is the provision of means whereby to guard against the placing of mail-matter in receptacles which are out of service temporarily or permanently, and it is designed to be utilized particularly in the case of mail-cars at the end of the run, as in the yards or shops of the railroad company.

It is to be understood that with slight modifications my invention may be adapted for use in connection with street letter-boxes, fare-boxes, vending-machines, and other depositories.

It is frequently noticed by those having to do with mail-cars that when the same are run upon sidings in railroad-yards or left standing for a time in any accessible place or when diverted for the purpose of being sent to the shops for repairs persons are prone through carelessness or ignorance of the destination of the car to drop mail-matter through the mail-box openings in the side of the car, thus entailing in many cases great delay in the transmission of such mail-matter and in some cases total loss of the same. With the object of avoiding such miscarriages I have devised a structure adapted to be applied at a small expense to such receptacles, and in the accompanying drawings, in which like letters of reference indicate corresponding parts throughout, I have illustrated an embodiment of my invention as applied to a mail-car of the ordinary type.

In the drawings, Figure 1 is a view of a portion of the wall of the mail-car so broken away as to disclose the arrangement and operation of my invention. Fig. 2 is an exterior view in perspective with the outer lid of the mail-box raised and showing the opening

unobstructed for the reception of mail-matter. Fig. 3 is a similar view showing what would confront one endeavoring to mail a letter in a car withdrawn from service. Fig. 4 is a detail view in elevation and section of means for securing the locking-lever in position, and Fig. 5 is a detached view of the means for closing the mail-box opening.

Referring to the drawings more in detail, A *a* are respectively the outer and inner walls of a mail-car, having mounted on the outside thereof the casing B, having the hinged lid *b*, adapted to cover and protect the opening C, communicating by the chute D with the interior letter-box E. Mounted in a suitable manner on the interior of the outer wall A, as by a pivot F, is the closure G, having its lower portion of such configuration as effectually to seal the opening C and bearing thereon a notice to the effect that the car is out of service or other appropriate legend. Hinged to the lower portion of said closure, as at H, is a lever I, projecting into the interior of the car through a slit J in the casting K and provided with notches L or other suitable means for engaging the lug M on the casting K in order to secure the lever in any desired position.

It will be seen that in the position illustrated in full lines in Fig. 1 the opening to the chute is effectually sealed, and any person attempting to mail a letter is upon raising the outer lid *b* confronted with the closed opening, having the information that the car is out of service, while, even were such a person disposed to force an opening to the chute, the closure is securely held in place by the locked lever I. When the car is to be taken out upon the road and is ready to receive mail, the mail clerk in the interior of the car takes hold of the lever I and raising the same out of engagement with the lug M and pulling the same inward and upward withdraws said closure from the opening and leaves the passage unobstructed for the entrance of mail-matter.

It will be obvious that this same device can be applied to street letter-boxes, boxes in use in the rural free delivery, or in connection

with depositories and receptacles of any sort. Wherefore I do not wish to be limited to the specific construction or application shown, other modifications and adaptations which 5 would readily suggest themselves being well within the scope of my invention, as described and claimed.

Having thus fully described my invention, what I claim as new, and desire to secure by 10 Letters Patent, is—

1. In a mail-receptacle provided with a conduit for the insertion of mail therein, the combination of means movable to obstruct the conduit, and mechanism extending exterior of 15 said receptacle and constructed to securely lock said movable means in either its closed or open position, substantially as described.

2. In a mail-receptacle provided with a conduit for the insertion of mail therein, the combination of a closure arranged to, in its closed position, obstruct the conduit, and a lever extending exterior of said receptacle, and constructed and arranged to securely lock said closure in either its closed or open position, 25 substantially as described.

3. In a mail-receptacle provided with a conduit for the insertion of mail therein, the combination of means movable to obstruct the conduit, said movable means constructed and positioned to constitute a visual signal when in 30 its closed position, and mechanism extending exterior of said receptacle and constructed to securely lock said movable means in either its

closed or open position, substantially as described.

4. In a mail-receptacle adapted to be positioned within a compartment, the combination of a conduit constructed to extend through a wall of such compartment and arranged in communication with the interior of said receptacle, means movable to obstruct said conduit, and mechanism accessible within said compartment and constructed to actuate said movable means and securely lock the same in either its closed or open position, substantially 40 as described.

5. In a mail-receptacle adapted to be positioned within a compartment, the combination of a conduit constructed to extend through a wall of such compartment and arranged in communication with the interior of said receptacle, means movable to obstruct said conduit, said movable means constructed and positioned to constitute a visual signal when in its closed position, and mechanism accessible 50 within said compartment and constructed to actuate said movable means and securely lock the same in either its closed or open position, substantially 55 as described.

In testimony whereof I affix my signature in 60 the presence of two subscribing witnesses.

HENRY H. WARNER.
